J. R. BROWN.

AIR LIFT PUMP.

APPLICATION FILED APR. 16, 1914.

1,180,281.

Patented Apr. 25, 1916.

UNITED STATES PATENT OFFICE.

JOHN R. BROWN, OF OIL CITY, LOUISIANA.

AIR-LIFT PUMP.

1,180,281.

Specification of Letters Patent.

Patented Apr. 25, 1916.

Application filed April 16, 1914. Serial No. 832,376.

To all whom it may concern:

Be it known that I, JOHN R. BROWN, a citizen of the United States, residing at Oil City, in the parish of Caddo, State of Louisiana, have invented certain new and useful Improvements in Air-Lift Pumps; and I do hereby declare the following to be a full, clear, and exact description of the invention, such as will enable others skilled in the art to which it appertains to make and use the same.

This invention relates to oil well apparatus and has special reference to a device for expelling the oil from a well by means of an air jet, the device being preferably termed an air lift pump.

The principal object of the invention is to provide an improved and simplified device of this description which may be used in connection with any ordinary oil well or other driven well, preferably with those having a tubular lining.

A second object of the invention is to provide a device of this character with an improved construction whereby it is properly centered in the well.

With the above and other objects in view the invention consists in general of certain novel details of construction and combination of parts hereinafter fully described, illustrated in the accompanying drawings, and specifically claimed.

In the accompanying drawings, like characters of reference indicate like parts in the several views, and Figure 1 is a section through an oil well showing the device in position therein. Fig. 2 is an enlarged detail section on the line 2-2 of Fig. 1. Fig. 3 is an enlarged detail section on the line 3-3 of Fig. 2. Fig. 4 is a detail view of the lower end of the air supply pipe removed from the rest of the apparatus.

In carrying out the object of this invention there is provided a tubular member 10 which is closed at the bottom as at 11 and is provided centrally of said bottom with a threaded recess 12 opening into the body of the member 10. Extending radially around the member 10 are certain centering flanges 13 which have their ends curved as at 14 and these flanges are so proportioned that they will fit neatly within the tubing of the well, the curved ends permitting ready introduction and withdrawal of the device 55 from said tubing.

At 15 is an air supply pipe which is made in sections in the usual way and the lower section of this pipe is provided with a threaded end 16 which is screwed into the threaded recess or socket 12 when the parts are assembled. The lower end of the pipe 15 is provided above the threaded portion with a multiplicity of perforations 17 through which the air may escape into the space between the pipe 15 and the wall of the member 10. These threaded perforations terminate somewhat short of the open end of the member 10. It is to be noted that the flanges 13, holding the members 10 spaced from the wall of the tubing in the well, provide spaces through which the oil or other liquid in the well may rise.

When the device is used the upper end of the tube 15 is connected to a suitable high pressure air compressor not deemed necessary here to be shown as the specific type of compressor does not form a part of this invention. The device is introduced into the well near the bottom thereof just above the ordinary check valve that is frequently employed in such wells. Air is then turned on and rushes violently out of the perforations 17 and up through the annular space left between the pipe 15 and the wall of the member 10. This upwardly rushing annular jet of air creates a partial vacuum around the member 10 and between said member and the tubing wall of the well. This causes the oil to rise in the spaces between the flanges and when the oil has risen until the air contacts therewith the out flowing jet of air entrains the oil in itself and forces the oil violently out of the well.

It is to be noted that the device can be readily applied to any existing well, is simple to use and has no part to get out of order. There has thus been provided a simple and efficient device of the class described and of the character specified.

It will be obvious that many minor changes may be made in the form and construction of this invention without departing from the material principles thereof. It is not therefore desired to confine the invention to the exact form herein shown and described, but it is wished to include all such as come properly within the scope claimed.

The casing of the well is indicated at A in Fig. 1 while B represents a portion of the usual string of tubing such as is pre-

ferred for a working valve and sucker rod and which is well adapted for the use of this lift.

Having thus described the invention, what is claimed as new, is:—

In a device of the kind described, a hollow cylindrical body member closed at one end, an air pipe fastened in the body member and provided with perforations in the part below the mouth of the body member, radial flanges extending from the outside of

the body member and continuing the whole length thereof, the ends of the flanges being rounded to permit easy withdrawal and introduction of said member into a well. 15

In testimony whereof, I affix my signature, in the presence of two witnesses.

JOHN R. BROWN.
